(57) CLAIM

The ornamental design for a bottle, as shown and described.

DESCRIPTION

FIG. 1 is a perspective view of a bottle showing a first embodiment of our new design;

FIG. 2 is a right side view thereof;

FIG. 3 is a left side view thereof;

FIG. 4 is back view thereof

FIG. 5 is a front view thereof.

FIG. 6 is a top view thereof;

FIG. 7 is a bottom view thereof; and,

FIG. 8 is a perspective view of a bottle showing a second embodiment of our new design, the remaining views being identical to the views shown in FIGS. 2-7 except for the showing of threads.

The broken line showing of threads in FIGS. 1-5 is for illustrative purposes only and forms no part of the claimed design.
